GEORGE L. WITSIL, OF PHILADELPHIA, PENNSYLVANIA, ASSIGNOR TO HIMSELF AND WILLIAM DARMON, AND GEORGE W. GRIFFIN, OF THE SAME PLACE.

Letters Patent No. 65,148, dated May 28, 1867.

IMPROVED CLOTHES-WRINGER.

The Schedule referred to in these Letters Patent and making part of the same.

TO ALL WHOM IT MAY CONCERN:

Be it known that I, GEORGE L. WITSIL, of Philadelphia, in the county of Philadelphia, and State of Pennsylvania, have invented a new and useful Improvement in Clothes-Wringers; and I do hereby declare that the following is a full, clear, and exact description of the same, reference being had to the annexed drawings, making part of this specification, in which—

Figure 1 is a perspective view.

Figure 2 is an end elevation; and

Figure 3 is a transverse vertical section.

The same letters are employed in all the figures in the indication of the same parts.

A and A' are elastic-faced rollers, which I prefer making of India rubber. The lower roller A is stationary, and the upper roller A' plays vertically so as to accommodate itself to the clothes passed between the rollers. B is the journal of the lower roller, which is turned by a winch, C. The journals of the upper adjustable roller A' are supported in the slotted frame D, passing through bearings D¹ and vertical slots in the side of the frame. The pin D² projects from the top of the bearing-blocks D¹ through a guide in the top of the frame D, which is also formed with guides on the inner face to retain the bearings, while permitting their free vertical play, as greater or smaller articles are passed between the rollers. A spiral spring, E, surrounds the pin D², bearing against the under side of the annular top of the frame and the upper face of the block D¹. This spring maintains the equality of the pressure on all articles subjected to the action of the wringer. This arrangement of bearings and springs is duplicated on the two journals. An arm, D³, on each side, extends from the bottom of the frame D. A curved bar, D⁴, connects the extremities of the two arms D³. The lower roller has its bearings in the side frames F. These frames are constructed with lugs F', to which the arms D³ of the adjustable frame D are pivoted, so as to permit an oscillatory motion to that frame. The arms F² of the frames F support the curved bar F³. These bars D⁴ and F³ form jaws to clamp the outside and inside of the upper edge of the wash-tub to which the wringer is attached. The thicker the article subjected to the action of the wringer may be, and the greater the strain upon the winch, the tighter will the jaws be compressed upon the sides of the tub. The lower roller is turned by the direct action of the winch C attached to its journal B. The upper roller is turned in the opposite direction by a spur-wheel, G, on the shaft B, driving a pinion, G', on the shaft of the upper roller outside of the slotted frame D. As the upper roller is to work at variable distances from the lower one, it is necessary to provide some means of retaining the spur and pinion in gear. This is effected as follows: The pinion is not fastened to the shaft directly, but a piece in the form of a Greek cross is fixed upon the shaft of the upper roller. The centre of the pinion has a slot in the same form, but with the arms of the cross made a little wider and enough longer to equal the play vertically of the upper roller. This pinion thus constructed is then attached by setting it upon the cross H, and a washer, I, outside of the pinion, is rigidly attached to the shaft to hold in place the pinion. As the spur-wheel G is turned, the teeth theron will continue to engage those of the pinion, notwithstanding the variations in the space between the rollers, as the slotted pinion will fall by its own gravity, and, sliding on the arms of the cross-formed hub, maintain the cogs in gear.

What I claim as my invention, and desire to secure by Letters Patent, is—

1. The combination of the roller A, spur-wheel G and frame F, including the jaws F² F³, and the roller A', adjustable pinion G' and frame D, including the jaws D³ D⁴, said parts being respectively constructed, and the whole arranged to operate substantially as and for the purpose set forth.
2. The arrangement of the rollers at A and A' when both are actuated positively, frames D and F, including the jaws F² F³ and D³ D⁴, block D¹, stems D², and spiral springs E, substantially as set forth.
3. In combination with the rollers A and A', the spur-wheel G and slotted pinion G', cross-piece H, rigidly attached to the shaft of the upper roller and washer I, substantially as and for the purpose set forth.

In testimony whereof, I have signed my name to this specification in the presence of two subscribing witnesses.

GEO. L. WITSIL.
